US0D1082867S

(12) **United States Design Patent** (10) **Patent No.:** **US D1,082,867 S**
(45) **Date of Patent:** **** Jul. 8, 2025**

(54) **MINING MACHINE**

(71) Applicant: **Normet Oy**, Iisalmi (FI)

(72) Inventors: **Antti Romo**, Jarvenpaa (FI); **Pasi Tolonen**, Iisalmi (FI)

(73) Assignee: **Normet Oy**, Iisalmi (FI)

(**) Term: **15 Years**

(21) Appl. No.: **29/873,139**

(22) Filed: **Mar. 27, 2023**

(30) **Foreign Application Priority Data**

Sep. 28, 2022 (EM) 009189590-0005

(51) **LOC (15) Cl.** **15-04**

(52) **U.S. Cl.**

USPC **D15/21**

(57) **CLAIM**

The ornamental design for a mining machine as shown and described.

DESCRIPTION

FIG. 1 is a front top perspective view of a mining machine showing our new design;

FIG. 2 is a left side elevational view of the design shown in FIG. 1;

FIG. 3 is a right side elevational view of the design shown in FIG. 1;

FIG. 4 is a top plan view of the design shown in FIG. 1;

FIG. 5 is a bottom plan view of the design shown in FIG. 1;

FIG. 6 is a front elevational view of the design shown in FIG. 1;

FIG. 7 is a rear elevational view of the design shown in FIG. 1; and,

FIG. 8 is a rear top perspective view of the design shown in FIG. 1.

The broken lines shown in the drawings form no part of the claimed design.

1 Claim, 8 Drawing Sheets
